UNITED STATES PATENT OFFICE.

DONALD E. BURGER, OF MOUNT VERNON, NEW YORK.

INDICATOR.

1,295,113.

Specification of Letters Patent.

Patented Feb. 25, 1919.

Application filed November 21, 1917. Serial No. 203,165.

To all whom it may concern:

Be it known that I, DONALD E. BURGER, a citizen of the United States, residing at Mount Vernon, in the county of Westchester and State of New York, have invented certain new and useful Improvements in Indicators, of which the following is a specification, reference being had to the accompanying drawings.

10 This invention relates to an improved indicator and has for its primary object to provide a very simply constructed, efficient and serviceable indicating device which may be advantageously used as a street or station indicator for cars and other vehicles, or which may be employed in connection with display advertising.

It is one of the more particular objects of the invention to provide two sets of rolls 20 mounted within a suitable casing and geared together, each roll set carrying a display web the ends of which are connected to the respective rolls, an actuating spring for each set of rolls, and interchangeable means to 25 operatively connect the springs with one of the rolls in each set.

It is another important object of my invention to provide electrically controlled means with which means on one of the webs 30 is adapted to coact whereby the webs are held against movement.

It is a further general object of my invention to provide a device for the above purpose which is highly efficient and reliable 35 in its operation and wherein the several parts are very compactly arranged so that the device will occupy but little space.

With the above and other objects in view the invention consists in the improved construction, combination and arrangement of the several parts as will be hereinafter more fully described, subsequently claimed and illustrated in the accompanying drawings in which similar reference characters designate 45 corresponding parts throughout the several views and wherein:

Figure 1 is a vertical sectional view through one end of the casing of the indicator showing the arrangement of the indicating tapes therein and the actuating means for said tapes.

Fig. 2 is a vertical sectional view taken on the line 2-2 of Fig. 1;

Fig. 3 is a section taken on the line 3-3 of Fig. 1;

Fig. 4 is a detail end elevation;

Fig. 5 is a section taken on the line 5-5 of Fig. 1;

Fig. 6 is a side elevation of the indicator;

Fig. 7 is a fragmentary perspective view 60 of one of the webs illustrating the relative arrangement of the solenoid core in the movement of the web;

Fig. 8 is a similar view showing one of the tapes or projections on the web engaged 65 with the solenoid core when the web is stationary;

Fig. 9 is a sectional view through the solenoid; and

Fig. 10 is a detail elevation of the winding 70 key for the roll springs.

Referring in detail to the drawings, 5 and 6 designate the top and bottom walls respectively, of a relatively narrow sheet metal casing which are connected at their 75 ends by integral end walls. One of these end walls of the casing designated 7 is formed contiguous to the top and bottom walls with cylindrical lateral extensions 8. The ends of these extensions have inwardly 80 pressed walls 9, each of which is centrally formed with an inwardly projecting tubular boss 10.

The opposite sides of the case are closed by means of the doors 11 which are hinged 85 at spaced points along their lower edges to the bottom wall 6 of the case as shown at 12. The free longitudinal edges of these doors are provided with slots to receive rotatable latch elements 13 suitably mounted 90 on the angular flanges 5' which are formed on the longitudinal edges of the top wall 5.

Within the case and at each end thereof a vertically disposed frame plate 13 is arranged, said plates being fixed at their ends 95 to the top and bottom walls of the case. Each of these plates is provided in one of its edges and adjacent its upper and lower ends with the correspondingly located inwardly and downwardly inclined bearing 100 seats or notches 14 and similar notches 15 are also provided in the other vertical edges of these frame plates, the latter notches however, being spaced from the notches 14. The ends of rolls 16 are engaged in the bearing 105 seats 14 and to these rolls the ends of a web 17 are attached in any suitable manner. Similar rolls 18 are engaged at their ends in the bearing seats 15 and a second web 19 is attached at its ends to these latter 110

rolls. These webs are opposed to the sight openings 20 in the hinged doors 11 of the case.

One of the upper rolls 16 and one of the 5 lower rolls 18 are respectively in axial alinement with the cylindrical projections 8 on the end wall of the case and the ends of said rolls which are opposed to the extensions 8 are formed with rectangular notches 10 21. The rolls 16 and 18 are operatively connected by means of the gear 22.

Within each of the extensions 8 on the end wall of the case, a bearing member 23 is arranged and secured to the wall of said 15 extension. In this bearing member, a rectangular sleeve 24 is rotatably mounted. One end of a spirally coiled spring 25 is fixed to this sleeve and the other end thereof is suitably attached, as at 26, to the bearing. 27 designates a key which has a rectangular shank 28 reduced at one of its ends as at 29, the other end of said shank being cylindrically formed, as shown at 30. This key is adapted to be inserted through either 25 of the bosses 10 and the rectangular portion of the key shank engaged within the sleeve 24, the reduced end 29 of the key shank fitting into the notch 21 in the end of the roll shaft 16 or 18 as the case may be.

30 The web 17 is provided from one of its edges with the spaced laterally projecting tabs or extensions 31, said tabs being spaced in accordance with the arrangement of the indicia upon the face of the web. The frame 35 bars 13 are connected by an angular rail 32 and upon this rail a solenoid 33 is mounted. The core 34 of this solenoid is normally projected by means of the coil spring 35, as clearly shown in Fig. 9 of the drawings into 40 the path of movement of the tabs or extensions 31 on the web 17. The solenoid is of course arranged in a suitable circuit, not shown, having a switch which may be actuated automatically upon the opening of a 45 door, or by means of a lever, pull cord, or other suitable device.

Having now described the construction and relative arrangement of the several parts of my improved indicator, its operation will 50 be understood as follows. After the rolls 16 and 18 carrying the webs have been inserted into the bearing seats in the frame uprights 13 and the doors of the case closed, the key shank 28 is inserted into one of the 55 sleeves 24, but the end of this key shank is not engaged in the notch 21 of the adjacent web roll. The key is then turned to wind the spring and place it under tension. The key is then pushed farther in to engage 60 the end 29 thereof in the notch 21 of the roll. Upon the release of the key, the spring will start to unwind and rotate the rolls 16 and 18 whereby the webs are moved. This movement will continue until one of the projecting tabs 31 on the webs 17 comes into en-

gagement with the solenoid core 34. When it is desired to change the street number or other indicia displayed by the web, the circuit is closed, to energize the solenoid whereby the core is retracted out of the path of 70 the tab 31 so that the web 17 may be moved. A corresponding movement is of course transmitted to the web 19 through the medium of the gears 22. The closing of the circuit is only momentary, and the solenoid 75 core is returned to its normal position by the spring 35 so that when the tab 31 contacts with the solenoid core the movement of the webs will be stopped, thereby displaying the successive names on the webs through the 80 respective sight openings 20. This operation continues until the webs are entirely wound upon one roll in each set, as for instance when the end of the route traversed by the car or vehicle is reached. The key is then 85 withdrawn from the bearing sleeve 24 and inserted into the other of the bearing sleeves so as to wind the other spring 25. The key is then operatively engaged with the end of the adjacent web roll in the manner above 90 stated, and upon the release thereof the webs are moved in a reverse direction to the former direction of movement, the solenoid core operating to control such movement of the webs as will be clearly understood from 95 the foregoing description.

From the foregoing description taken in connection with the accompanying drawing, the construction, manner of operation and several advantages of the device will be fully 100 and clearly understood. My improved indicator is serviceable and reliable in its operation, and consists of relatively few parts which are very compactly arranged. The device is not liable to get out of order, but on the contrary is very durable and may also be manufactured at comparatively small cost. It will be of course appreciated that the movable webs can be of any desired 105 length, and the arrangement of the printed matter or other display means thereon can be varied as desired.

While I have herein shown and described the preferred construction and arrangement of the several elements employed, it is to be understood that the device is susceptible of considerable modifications therein and I therefore reserve the privilege of adopting all such legitimate changes as may be fairly embodied within the spirit and scope of the 120 invention as claimed.

Having thus fully described my invention, what I claim and desire to secure by Letters Patent is:—

1. In an indicator, in combination with 125 spaced rolls and a web connecting the same, an operating spring, a winding key for the spring, and means for detachably connecting the key to one end of the spring, said key having means adapted to be operatively con-

nected with one end of one of the rolls after the spring is wound to operatively connect the spring to said roll.

2. In an indicator, in combination with 5 spaced rolls and a web connecting the same, a rotatable part in axial alinement with one of the rolls, an operating spring connected at one end to said rotatable part, and a key adapted for engagement with the rotatable 10 part to wind the spring, said key and the

web roll having coacting means engageable by a subsequent axial movement of the key to operatively connect the spring to the roll.

In testimony whereof I hereunto affix my signature in the presence of two witnesses. 15

DONALD E. BURGER.
